US0D1101940S

(12) **United States Design Patent** (10) **Patent No.:** **US D1,101,940 S**
(45) **Date of Patent:** **** Nov. 11, 2025**

(54) **SYRINGE GRIP**

(71) Applicant: **GALDERMA HOLDING SA**, Zug (CH)

(72) Inventors: **Oscar Ullsten**, Uppsala (SE); **Sofie Strähle**, Uppsala (SE)

(73) Assignee: **Galderma Holding SA**, Zug (CH)

(**) Term: **15 Years**

(21) Appl. No.: **29/936,588**

(22) Filed: **Apr. 9, 2024**

(57) **CLAIM**

The ornamental design for a syringe grip as shown and described.

DESCRIPTION

FIG. 1 is a front, top, right perspective view of a syringe, shown in condition of use for clarity of disclosure; FIG. 2 is a rear, bottom, left perspective view thereof; FIG. 3 is a front, top, right perspective view of a syringe grip of the syringe of FIG. 1;

FIG. 4 is a rear, bottom, left perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The equal-length broken lines in the drawings depict portions of the syringe grip that form no part of the claimed design. The equal-length broken lines in FIGS. 1 and 2 showing a syringe and needle depict environmental structure and form no part of the claimed design. All broken lines form no part of the claimed design.

1 Claim, 9 Drawing Sheets
